[57] CLAIM

The ornamental design for a camper mounting cushion for the top surface of the sidewalls of a truck bed, as shown and described.

DESCRIPTION

FIG. 1 is a front elevational view of a camper mounting cushion for the top surface of the sidewalls of a truck bed showing my new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof.

The right and left sides of the camper mounting cushion have been broken away in the middle in all views to indicate indeterminate length.
